UNITED STATES PATENT OFFICE.

JAMES C. REID, JR., OF CLEVELAND, OHIO, ASSIGNOR TO JAMES C. REID, SR., OF CLEVELAND, OHIO, AND WILLIAM C. TAYLOR, OF EAST CLEVELAND, OHIO.

TOE-PLATE SETTER.

Application filed May 22, 1924. Serial No. 715,125.

To all whom it may concern:

Be it known that I, JAMES C. REID, Jr., a citizen of the United States, residing at Cleveland, in the county of Cuyahoga and State of Ohio, have invented new and useful Improvements in Toe-Plate Setters, of which the following is a specification.

This invention relates to devices used by shoemakers, dealers and cobblers for setting metallic wearing plates on the bottoms of the soles of shoes at or near the toe.

Pounding metallic toe-plates into shoes on an iron last with a hand hammer is crude, and difficult to accomplish without distorting the plate or bending its prongs, and seldom sets it flush with the sole. Thus the main object of the present invention is to provide convenient, simple and efficient means for fastening toe-plates to shoes in a workmanlike manner, firmly and speedily, and embodied in a self-contained device fixed to a table, counter, or other convenient support, and always ready for use. Another important object is to eliminate the lost motion, and lateral and endwise play, which occurs between the reciprocating ram and the last or anvil in existing machines and operates against accurate setting of the toe-plates, and to accomplish this without sacrificing the advantages of plate pressing means made slidable or otherwise movable relatively to the last. Also, to provide means in connection with the pressing mechanism for locking the last in its upright position while the toe-plate is being set; and for preventing depression of the ram while the last member is tilted to receive or discharge a shoe. A further object is found in the gripping device for receiving and holding a toe-plate in position beneath the bottom face of the ram, and its means for releasing, clearing and retracting automatically.

Minor objects will become apparent from the following description of a preferred embodiment of my invention, reference being had to the accompanying drawings, in which—

Fig. 1 is a side elevation of an assembled machine, the dotted lines indicating the toe part of a shoe upon the last member.

Fig. 2 is a side view of the machine showing the pressing means depressed.

Fig. 3 is a front elevation of Fig. 1.

Fig. 4 is a sectional elevation taken on line 4—4 of Fig. 1.

Figs. 5 and 6 are sectional plan views taken respectively on lines 5—5 and 6—6 of Fig. 2.

Figs. 7 and 8 are detailed fragmentary sectional elevations, the former showing the pressure ram device at its upper position, and the latter showing said ram and connections at the bottom of its travel.

Fig. 9 is a front view of the lower part of the ram and gripper.

Fig. 10 is a bottom view of a toe-plate and gripping fingers.

In general arrangement the device parts of the nature of a press, in which the reference numeral 1 indicates the base-plate of the machine frame, which supports an upright standard 2 of I-shaped cross-section to carry the pressing mechanism, and a forwardly extending rib 3 terminating in a transverse bearing block 4 to support the anvil members. Holes are made in the base-plate for screws 5 to secure the machine to a table, counter, or other support 6. A circular boss or hub 7 projecting forward from the standard 2 is drilled to receive the inner end of the anvil supporting shaft 8, the outer end of which extends through a hole in the bearing block 4, so that the shaft serves as a hinge pin for the last member. A cotter pin 9 keeps the shaft 8 in place.

The U-shaped last member, or anvil, comprises a blunt-pointed, flat-topped and lanceolate, or trowel-shaped metallic toe last 10 integral with and supported upon a flat, or I-sectioned, and return-bent gooseneck 11 bent forward, downward and rearward, and merging at its lower end in a horizontal base bar 12. The toe of the last head 10 is preferably provided with a slightly elevated boss 13, the top of which may be filed or ground into shape to assure proper setting of toe-plates in either new or worn soles, or to suit other conditions of service. The base-bar 12 has depending from it a pair of hinge-lugs 14 and 15 drilled in alignment to receive and oscillate upon the anvil shaft 8; and the spacing apart of said lugs is shorter than the distance between the boss 7 and bearing block 4, as shown, to permit endwise movement of the last sufficient for adjustment required to properly locate the toe-plate on a shoe such as indicated by dotted

lines at 46 in Fig. 1. To facilitate said adjustment laterally projecting ears 16 and 17 are formed on the base-plate 1—3, and the rear hinge-lug 15 is likewise lobed at 18, as best shown in Figs. 1 and 4, so that said projections may be conveniently grasped and the required movement effected by the operator's hand. The base and press frame being rigid, and the point where pressure is applied to the last 10 being above and between the hinged supports 14 and 15, prevents longitudinal play between the die and last members relatively, such as occurs in the absence of this rigidity and direct central bearing. This insures a firm and accurate setting of the toe-plate.

Stop shoulders 19 and 20, best shown in Fig. 4, are formed on the lower edge of the hinge-lug 15 to limit the lateral rocking of the last, or anvil member, by abutting against the girder rib 3. The base-bar 12 is preferably reduced in height at its rear end; and carries here a wing-like stop-lug 21 projecting horizontally rearward and offset to the side, opposite to that in which the last swings, in a cylindrical curve substantially concentric with the shaft 8; its median edge 22 being parallel with the said shaft, and adapted to co-operate with the stop 19 and locking means hereinafter described to hold the last member in its upright position.

Above and adjacent to the wing 21 a bearing lug 23 juts out from the standard 2, from which point the standard rises vertically at its front, and supports a pressure head 24 bracketed out therefrom to overhang the last nose 13, and provided with a bearing in which a ram or plunger 25 may reciprocate vertically. Means for retracting and normally supporting the ram at the top of its stroke comprise a rod 26 vertically disposed in bearing holes through the head bracket 24 and lug 23, with its upper end 27 bent at right angles and inserted in an aperture drilled horizontally part way through the ram 25 near its top; and a coiled spring 28 encircling said rod and compressed between the lug 23 and a stop-pin 29 fixed to the rod. Another stop-pin 30 abuts against the bottom of the bracket 24 to limit the upward travel of the rod and ram; but stop collars may be substituted in place of the pins 29 and 30 if desired. When the ram 25 is depressed the lower end of the retractor rod 26 is projected beneath the lug 23, and interlocks with the edge 22 of the stop-wing 21, so that the last member 10 cannot be tilted from its upright position while a toe-plate is being set. But should the last member be inclined, as shown by dotted lines in Fig. 3, or merely tilted a little from its normal operative position, then the upper face of the stop-wing 21 is interposed beneath the rod 26, and prevents depression of the ram mechanism. Thus a

toe-plate cannot be driven without locking the last in its upright position.

For depressing the ram 25 various known devices are more or less adaptable; but a simple hand-lever 31 is preferred, having a curved cam surface at 32 eccentric or involute to its fulcrum pin 33, and mounted between branches 34 of a forked standard rising from the head bracket 24. The pin 33 is set somewhat forward of the axis of the ram 25, and the head of the ram is engaged by the cam 32, and forced down as the lever 31 is swung backward and downward to the position shown in Fig. 2. A stop-lug 35 on the lever 31 abuts against a pair of projections 36 on the respective forks 34, and holds the lever poised as in Fig. 1 when the device is at rest.

The lower end of the ram 25 is chamfered off somewhat as at 37, and hollowed out to form a die concavity approximately fitting the convex crown of a toe-plate 38. The toe-plate shown herein is circular in contour, as in Fig. 10, and has three prong-like claws or tangs 39 bent at right angles to the plane of its edges; but oblong, ovoid and other shapes are made, and can be set by this machine without more than slight changes, if required, in the die end of the ram.

The lower part of the ram shaft 25 is turned to a smaller diameter than its body, so that an abrupt shoulder is formed at 40, and a collar 41 is slidably mounted thereon against the thrust of a helical spring 45 in compression between the collar and the said shoulder. Gripping fingers 42 of small spring wire, at least three of them, are fixedly secured in the lower edge of the collar 41, extend downward along and somewhat below the die end of the ram, and terminate in loops 43. Balls, or heads of other shape can be substituted in place of the said loops, but loops are more readily formed and easily adjusted. A pair of short pins 44 driven into the ram shaft, one on each side of the front wire finger 42, serve as a stop beneath the slip-collar 41, and keep it from turning on the ram shaft.

To operate the device, a toe-plate 38 is pushed up against the die end 37 of the ram, the wires 42 springing easily outward to receive the plate and snapping back to hold it against the die as in Fig. 7. The last member 10 being tilted as shown in dotted lines in Fig. 3, a shoe 46 is readily slipped over it, whereupon the last is raised to its upright position, and locked therein by the lower end of the rod 26 directly as the ram begins to be depressed by the hand-lever 31. As the ram descends the last member 10 to 12 may be shifted slightly endwise to properly place the toe-plate on the sole of the shoe, and then the toe-plate is driven hard into the sole as shown in Fig. 8. When the looped ends 43 of the spring fingers strike 130

the sole of the shoe 46, they are forced outward by the toe-plate and release it, while the ram descends through the slip-collar 41, thereby compressing the spring 45, which 5 restores the gripper to its normal position when the ram is retracted.

I further point out and distinctly claim as my invention—

1. A toe-plate setter for shoes comprising 10 a return-bent and laterally oscillable anvil member, and a pressing device having a ram adapted to be reciprocated in opposition to the anvil member, the ram being provided with means for interlocking with 15 the anvil member.

2. A toe-plate setter for shoes comprising a return-bent and laterally oscillable anvil member, a pressing device having a ram adapted to be reciprocated in opposition to 20 the anvil member, and a connection to said pressing device adapted to engage said anvil member and to lock the latter on the approach thereto of the ram.

3. A toe-plate setter for shoes comprising 25 a return-bent and laterally oscillable anvil member, a pressing device having a ram adapted to be reciprocated in opposition to the anvil member, a locking member connected with the pressing device, and a stop 30 on the anvil member arranged to intercept said locking member to prevent movement of the ram except when the anvil member is properly opposed to the ram.

4. In a toe-plate setter, a pressing device 35 having a vertically reciprocable ram mounted on a standard arising from a base-plate, a last beneath said ram supported upon a return-bent arm rigidly subtended by a horizontally extended base-bar, and a horizontal hinge-pin paralleling and rotatably and slidably connecting the base-bar to the base-plate.

5. In a toe-plate setter, a pressing device 45 having a vertically reciprocable ram mounted on a standard arising from a base-plate, a last beneath said ram supported upon a return-bent arm a base-bar, a hinge axially parallel to the base-bar permitting lateral oscillation of the last on the base-plate, 50 and stops adapted to limit the travel of the last.

6. In a toe-plate setter, a pressing device having a vertically reciprocable ram mounted on a standard arising from a base-plate, a last beneath said ram supported upon a 55 return-bent arm merged in a base-bar, a horizontal hinge-pin rotatably and slidably connecting the base-bar to the base-plate, a thrust-rod connected with the pressing device, and a stop-wing on said base-bar 60 adapted to intercept the thrust-rod and only permit depression of the ram when the last is at the top of its course.

7. In a toe-plate setter, a return-bent last member laterally oscillable upon a base-plate, a standard on the base-plate bearing a vertically reciprocable ram overhanging the last member, a thrust-rod mounted vertically on the standard and operatively connected at its upper end with the ram, and 70 stop means on said last member adapted to intercept and to interlock with the lower end of said thrust-rod.

8. In a toe-plate setter, a return-bent last member laterally oscillable upon a base-plate, a standard on the base-plate bearing a vertically reciprocable ram overhanging the last member, a thrust-rod mounted vertically on the standard and operatively connected at its upper end with the ram, a 80 retracting spring on the thrust rod, means for applying power to depress the ram, and a stop-wing on said last member adapted to intercept the thrust-rod and to clear the latter when the last member is directly opposed beneath the ram.

9. In a toe-plate setter, a last member adapted to receive and support a shoe, a longitudinally reciprocable ram mounted in opposition to the last member and having the shank of its driving end reduced in diameter to a shoulder, a collar slidable on said ram shank having three or more spring wire fingers extended lengthwise of the ram and terminating in loops normally overlapping the ram end, a pair of stops projecting from the ram shank embracing one of said fingers and limiting longitudinal movement of the collar, and a spring coiled about the ram shank in compression between 95 the collar and said shoulder.

JAMES C. REID, JR.
